ALFRED FRANCIS.

UNITED STATES PATENT OFFICE.

CATHERINE O'HARA, OF NEW YORK, N. Y., ASSIGNOR TO THE BUTTERICK PUBLISHING CO., (LIMITED,) OF SAME PLACE.

DESIGN FOR A LADY'S WRAP.

SPECIFICATION forming part of Design No. 14,380, dated October 30, 1883.

Application filed August 23, 1883. Term of patent 3 $\frac{1}{4}$ years.

To all whom it may concern:

Be it known that I, CATHERINE O'HARA, of the city, county, and State of New York, have invented and produced a new and original Design for a Pattern of a Lady's Wrap, (numbered 8,849;) and I do hereby declare that the engraved prints accompanying this specification convey to any one accustomed to using paper patterns a clear understanding of how 5 a garment made up by the pattern will appear.

The design combines deep sack fronts, straight at the lower edge for some distance back of the closing, curved high at the sides, and extended to join a back-skirt portion that

is laid in a double box-plait at the top, is short 15 at the center, and falls in points at the sides, a short, half-fitted back falling over the back skirt, deep, wide sleeves falling in square corners at the hands, and a standing collar.

What I claim as my invention, and desire to 20 secure by Letters Patent, is—

The design for a lady's wrap, as shown in the engraved prints accompanying this specification.

CATHERINE O'HARA.

Witnesses:
